(57) **CLAIM**

The ornamental design for a bar gun, as shown and described.

DESCRIPTION

FIG. 1 is a top plan view of a bar gun showing my new design; FIG. 2 is a left side elevational view thereof; FIG. 3 is a bottom plan view thereof; FIG. 4 is a right side elevational view thereof; FIG. 5 is a front elevational view thereof; FIG. 6 is a rear elevational view thereof; FIG. 7 is a perspective view thereof; FIG. 8 is a cross-sectional view thereof taken along line 8-8 in FIG. 2; and, FIG. 9 is a cross-sectional view thereof taken along line 9-9 in FIG. 2.
The drawing is lined for color (red). The broken line showing of portions of the bar gun is for the purpose of illustrating portions of the bar gun and forms no part of the claimed design.
